UNITED STATES PATENT OFFICE.

ERVIN E. LARRABEE, OF WILLIAMSTON, MICHIGAN.

BOILER.

No. 879,056.

Specification of Letters Patent.

Patented Feb. 11, 1908.

Application filed July 26, 1907. Serial No. 385,601.

To all whom it may concern:

Be it known that I, ERVIN E. LARRABEE, a citizen of the United States, and a resident of Williamston, in the county of Ingham and State of Michigan, have invented a new and Improved Boiler, of which the following is a full, clear, and exact description.

The object of the invention is to provide a new and improved boiler or heater of the water-tube type, and arranged for generating steam or for use in hot water heating systems for heating the water, the boiler being arranged to utilize the heat units of the burning fuel to the fullest advantage, to provide a large heating surface in a comparatively small space, to insure rapid circulation of the water and quick heating thereof for steam generating purposes or for heating purposes, as the case may be.

The invention consists of novel features and parts and combinations of the same, which will be more fully described hereinafter and then pointed out in the claims.

A practical embodiment of the invention is represented in the accompanying drawings forming a part of this specification, in which similar characters of reference indicate corresponding parts in all the views.

Figure 1 is a front elevation of the improvement arranged as a steam generator; Fig. 2 is a side elevation of the same; Fig. 3 is an enlarged cross section of the same on the line 3—3 of Fig. 2 with the casing removed; Fig. 4 is an enlarged sectional side elevation of the same on the line 4—4 of Fig. 1; Fig. 5 is an enlarged sectional plan view of the same on the line 5—5 of Fig. 3; Fig. 6 is an enlarged cross section of a modified form of the improvement; Fig. 7 is an enlarged sectional plan view of the same on the line 7—7 of Fig. 6; Fig. 8 is an enlarged cross section of another modified form of the improvement; Fig. 9 is an inverted sectional plan view of the same on the line 9—9 of Fig. 8; Fig. 10 is a front elevation of the improvement arranged as a hot water heater, and Fig. 11 is a side elevation of the same, part of the brick work being broken out.

The casing or shell A of the steam generating boiler shown in Figs. 1, 2, 3 and 4 is preferably made of metal lined with asbestos or a like material, and the said casing is provided at its front with the usual doors A' and at the

top with a smoke stack A². In the casing or shell A are mounted longitudinally extending lower or mud drums B, B' located near the sides of the casing A, and in the top middle portion of the casing is arranged a longitudinally extending upper drum C. The rear ends of the lower drums B, B' are connected with each other by a transverse tube D connected by a feed water pipe E with a feed water pump or the like for supplying the boiler with water. From the middle of the transverse tube D extends a branch pipe D' connected with the upper drum C. The front ends of the lower drums B, B' extend beyond the front of the casing or shell A, as plainly indicated in Figs. 1 and 2, and the said front ends of the lower drums B and B' are connected by vertically disposed tubes F and F' with a transversely extending steam drum G arranged outside of the casing A and provided on top with a steam dome H from which leads a steam pipe I for conducting the generated steam to an engine or other device in which the steam is to be used. The forward end of the upper drum C is connected by a pipe C' with the steam dome H, to conduct the steam from the upper drum C into the steam dome H. As indicated in Figs. 1 and 2, the drum G is arranged a distance below the upper drum C.

The grate J of the boiler is arranged between the lower or mud drums B, B' and their rear tube connection D. Each of the lower or mud drums B, B' is connected by sets of water tubes K, K' with the upper drum C, the said sets of water tubes K and K' extending along the sides and top of the fire box, so that the burning fuel on the grate J heats the said sets of pipes and the water contained therein, to insure a proper circulation of the water and quick generation of the steam.

Each of the sets of water tubes K and K' is arranged as follows: Tubes K² and K³ are connected with the drums B (B') and C, respectively, and the said tubes K², K³ lead to unions or heads K⁴, K⁵, connected with each other by a plurality of water tubes K⁶, staggered relative one to the other, as plainly indicated in Fig. 5, so as to form rows of inner and outer water tubes. The water tubes K⁶ rise from the unions K⁴ straight up at the sides of the fire box, then bend inward to

wards the middle of the fire box, to form the top thereof, the tubes then bending again outward, then inward and finally upward to connect with the unions K^5 , as plainly indicated in Fig. 3. By the arrangement described each set of tubes K or K' has but a single connection with the corresponding drum B , B' or C , and still the plurality of tubes are in each set and form the sides and top of the fire box, the tubes being staggered so that the heat developed by the burning fuel in the fire box thoroughly heats the water in the said tubes, to insure quick heating of the water and quick generation of steam.

15 By arranging the drum G in the manner described the water level can be readily maintained in the boiler a distance below the drum C , so that the steam in the upper ends of the sets of tubes K , K' can readily pass 20 into the drum C , and from the latter by way of the branch pipe C' into the steam dome H .

The sets of tubes K and K' may be provided with additional pipes, as indicated in Figs. 6, 7 and 8, 9, that is, in addition to the 25 pipes K^6 each set has an additional shorter pipe K^7 connecting the unions K^4 and K^5 with each other, the said tube K^7 being inside the other tubes and extending vertically from the union K^4 , then inward, then upward, 30 to connect with the other union K^5 , as plainly indicated in Fig. 6. By this arrangement a quicker circulation of water is had by way of the tube K^7 than in the tubes K^6 .

As illustrated in Fig. 8, each set of tubes K or K' is provided, besides the tubes K^6 , with a tube K^8 rising from the union K^4 to terminate in a union K^9 , from which leads a plurality of tubes K^{10} to the union K^5 . From the foregoing it will be seen that any number 40 of tubes may be connected in various ways with the unions K^4 and K^5 , and hence I do not limit myself to the particular arrangement of tubes shown and described, as the same may be varied without deviating from 45 the spirit of my invention.

In the water heater illustrated in Figs. 10 and 11, the casing A^3 is in the form of brick-work and the lower and upper drums B^2 and C^2 are located outside of the casing A^3 , and 50 are connected with each other at the ends by tubes L and sets of tubes N , similar to the sets of tubes K and K' connecting the drums B^2 and C^2 with each other between the end tubes L . Each of the sets of tubes N is connected by the pipes N' , N^2 with the drums B^2 and C^2 and the said tubes N' , N^2 are provided with unions or heads N^3 , N^4 connected with each other by a plurality of tubes N^5 arranged similar to the tubes K^6 previously 55 mentioned. The casing A^3 is provided with the usual front doors A^4 , smoke stack A^5 and a grate J' , and the drum B^2 preferably extends transversely at the rear of the casing A^3 , and into it lead the return pipes B^3 of the

water heating system, while the drum C^2 65 extends transversely at the top front portion of the casing A^3 , and from it lead the outlet pipes C^3 for conducting the hot water to the radiators of the hot water heating system.

The connecting tubes N^5 extend from their 70 unions N^3 , in the rear of the casing A^3 , upward, then forward, then rearward and then forward, to finally connect with the unions N^4 arranged in the front upper portion of the casing A^3 , as indicated in Fig. 11. By the 75 arrangement described the burning fuel on the grate J' is utilized to the fullest advantage as the heat reaches every one of the pipes N^5 , to insure quick heating of the water circulating therein.

80 Although I have shown a heater arranged for hot water heating system in Figs. 10 and 11, it is evident that I do not limit myself to this particular use of the heater.

Having thus described my invention, I 85 claim as new and desire to secure by Letters Patent:

1. A boiler comprising a pair of lower longitudinal drums, an upper longitudinal drum, sets of water tubes connecting the 90 upper drum with the lower drums, the said sets of water tubes extending along the sides and top of the fire box of the boiler, and each set of water tubes having single connections with the said drums, a plurality of tubes 95 between the connections, a transversely extending steam drum arranged somewhat below the said upper drum and connected with one end thereof, a steam dome on the top of the said steam drum, pipes connecting 100 the said steam drum with the said lower drums, a feed water pipe connecting the said lower drums with each other, and a branch pipe leading from the said feed water pipe to the said upper drum.

105 2. A steam boiler comprising spaced parallel mud drums, a feed water tube connecting the drums, an upper drum arranged between and above the mud drums and substantially parallel therewith, a branch pipe 110 connecting the feed water tube with the upper drum, sets of water tubes connecting the upper drum with the mud drums, the said sets of water tubes being arranged along the sides and top of the fire box of the boiler, a 115 transverse steam drum in front of and at a lower level than the upper drum, pipes connecting the steam drum with the mud drums, a steam dome on the steam drum, and a connection between the steam dome and the 120 upper drum.

3. A steam boiler comprising spaced parallel mud drums, a feed water tube connecting the drums, an upper drum arranged between and above the mud drums and substantially parallel therewith, a branch pipe 125 connecting the feed water tube with the upper drum, a plurality of water tubes connecting

the upper drum with the mud drums, a transverse steam drum above and below the level of the upper drum, pipes connecting the steam drum with the mud drums, a steam 5 dome on the steam drum, and a connection between the steam dome and the upper drum.

In testimony whereof I have signed my

name to this specification in the presence of two subscribing witnesses.

ERVIN E. LARRABEE.
